ABSTRACT

A self shift display panel driving system in which a discharge spot produced by written information is shifted by sequential switching of an impression voltage; a stationary display of the written information by the discharge spot is provided by the application of the impression voltage to a predetermined electrode; and the shift action is effected at high speed and stabilized by the impression of a voltage higher than a sustain voltage for the stationary display.

SHEET 1 OF 3

FIG. I PRIOR ART

FIG. 2

SELF SHIFT DISPLAY PANEL DRIVING SYSTEM

BACKGROUND OF THE INVENTION

1. Field of the Invention

This invention relates to a self shift display panel driving system in which display information is written while sequentially shifting a discharge spot.

2. Description of the Prior Art

A self shift display panel has a construction such, for example, as depicted in FIG. 1, in which electrodes w , $a_1, b_1, c_1, a_2, \dots$ are disposed on a first base plate 1 of glass and covered with a dielectric layer 2; electrodes y_i and write electrodes R_i ($i=1, 2, \dots$) are disposed on a second base plate 3 and covered with a dielectric layer 4; and a discharge gas such as neon or the like is sealed in the space 5 defined between the base plates 1 and 3. The electrodes $w, a_1, a_2, \dots, b_1, b_2, \dots$ and $c_1, c_2, \dots$ are connected to buses W, A, B and C, respectively, and the electrodes y_i are interconnected. By the application of a write voltage higher than a firing voltage between a selected one of the write electrodes R_i and the electrode W, a discharge spot is produced at their intersecting point. Then, in such a state that the electrodes y_i are all grounded or supplied with a predetermined voltage, the impression of a voltage between the electrodes y_i and the bus A, which is slightly higher than the firing voltage of neighboring electrodes, which is lowered under the influence of the primary current effect by the first discharge spot produced between the electrodes R_i and W, causes a discharge spot between the electrodes a_1 and y_i . Then, by impressing a similar voltage to the bus B and cutting off the voltage to the bus A, the discharge spot is shifted between the electrodes b_1 and y_i . Namely, the information written in the selected one of the electrodes R_i is shifted in the form of a discharge spot to the left, as seen in FIG. 1, by the sequential voltage impression to the buses A, B and C. When the changeover of the voltage is stopped at a desired shift position, the discharge spot also is stopped on the electrode leading to the bus being supplied with the voltage at that time, thus providing a display in a stationary condition. Namely, in this type of self shift panel, it is possible to shift serially written information in the form of a discharge spot from one side of the panel and provide its stationary display at any time by making use of the memory function due to a wall charge.

There has also been proposed the so-called surface discharge type self shift panel which does not employ the electrodes y_i in FIG. 1 and which is adapted such that a discharge spot is produced between adjacent ones of the electrodes $a_1, b_1, c_1, \dots$ and shifted.

Incidentally, in the above-described self shift panel, it is necessary that wall charges remaining in the wall at positions corresponding to electrodes energized previously be sequentially erased in accordance with the shift operation. If the wall charge remains alive, when a voltage of the next cycle is impressed through the common bus, the discharge spot is likely to be produced again to cause an erroneous display although no information has been shifted to the corresponding intersecting point of the electrodes. To avoid this, it is the practice in the prior art to impress an erasing pulse to the preceding electrode at the instant the discharge spot is shifted to an adjacent electrode intersecting point or prolong the cycle of voltage changeover to

such an extent as to be equal to the time necessary for neutralization and extinction of the wall charge; but, in either case, the shift action is unstable and high-speed shift is difficult.

SUMMARY OF THE INVENTION

The present invention is to provide a novel self shift display panel driving system which is free from the aforementioned defects experienced in the prior art and which utilizes the fact that a firing voltage and a minimum sustain voltage at adjacent electrode intersecting points differ in accordance with the magnitude of an impressed voltage, thereby ensuring and facilitating the shift action and automatically erasing a wall charge following each step of the shift action.

Briefly stated, the self shift display panel driving system of this invention is of the type in which a discharge spot is shifted by sequential changeover of an impression voltage and written information is displayed with a predetermined sustain voltage at any time and which is characterized in that the discharge spot is shifted while impressing a voltage higher than the sustain voltage for the display.

BRIEF DESCRIPTION OF THE DRAWINGS

FIG. 1 is a cross-sectional view of the principal part of a prior self shift display panel;

FIG. 2 shows characteristic curves for explaining the principle of this invention;

FIG. 3 is a circuit diagram illustrating an embodiment of this invention; and

FIGS. 4A and 4E show a series of waveforms for explaining the operation of the embodiment of FIG. 3.

DESCRIPTION OF THE PREFERRED EMBODIMENTS

The present invention has found, in connection with such a self shift display panel as described previously, that where a discharge is being produced between opposing electrodes, the firing voltage and the minimum sustain voltage between neighboring opposing electrodes are affected by the discharge in accordance with the magnitude of the impression voltage for the discharge. For example, in FIG. 2, where a discharge is being produced between the electrodes y and x_1 , if the impressed voltage therebetween is high, the firing voltage V_f and the minimum sustain voltage V_{sm} between the other adjacent electrodes become that as indicated respectively by the curves b and b' , and if the impression voltage is low, they become as indicated by the curves a and a' . Namely, if the impressed voltage is raised, the firing voltage V_f between adjacent electrodes y and x_2 lowers, for example, from V_{fa} to V_{fb} , allowing ease in the self shift action. At the same time, the minimum sustain voltage V_{sm} rises, so that an increase in the voltage for discharging after shifting, decreases wall charges between previously energized electrodes to facilitate erasing of the wall charges. Further, the difference between the firing voltage between subsequent electrodes y and x_3 and that between those y, x_2 adjacent to them is ΔM_1 when the impressed voltage between the electrodes y and x_1 between which the discharge spot is being produced is low and the difference is ΔM_2 when the impressed voltage is high. The greater the difference ΔM becomes, the more stable the self shift action becomes. An increase in the im-

pressed voltage causes an increase in the difference ΔM .

In order that the discharge spot being displayed stationary by the sustain voltage V_1 between the electrodes y and x_1 may be shifted to electrodes y and x_2 by utilizing the above-described phenomenon, first a voltage V_2 higher than that V_1 is impressed between the electrodes y and x_1 , and y and x_2 to provide a discharge spot on the electrodes x_1 and x_2 in common; thus, first the voltages V_1 and V_2 are impressed to the electrodes x_1 and x_2 , respectively; and then the voltage impressed upon the electrode x_1 is removed. Thus, the discharge spot is shifted and, at the same time, the discharge spot between the electrodes y and x_1 is extinguished so that the wall charge is reduced. Consequently, the wall charge remaining in the wall at the position corresponding to the previous electrode x_1 can be erased positively by a neutralizing action in a relatively short time or by the impression of an erasing pulse. Further, shifting of the discharge spot between the pair of electrodes y and x_2 to between electrodes y and x_3 also is achieved by similar procedures. This facilitates the shifting and ensures erasing of the remaining wall charge. In the prior art, the sustain voltage for the display operation and the shift voltage for the shift operation both are selected to be higher than the firing voltage at the position of adjacent electrodes subject to the primary current effect but, in the present invention, the impressed voltages V_1 and V_2 for both operations are different from each other.

FIG. 3 is a circuit diagram of one embodiment of this invention, which is shown to be applied to a self shift display panel SSP of two-dimensional shift. Reference characters V_{R1} , V_{R2} , ..., V_{Ri} designate write pulse voltages; V_w a voltage of the bus W ; V_{A1} , V_{B1} and V_{C1} voltages applied to the buses A , B and C ; V_D , V_{AR} , V_{BR} and V_{CR} voltages applied to buses D , AL , BL and CL ; and V_1 , V_2 and V_3 voltages shown in FIG. 2 are selected to comply with the shift voltage and the write voltage and have rise and fall times controlled by transistors. Opposing parts of the electrodes connected to the buses W , A , B , C and AL , BL , CL serve as an input part 20 and opposing parts of the electrodes connected to the buses AL , BL , CL and D serve as a display part 22. In the input part 20, written information is shifted sequentially in a horizontal direction as seen in FIG. 3 and, in the display part 22, the information is shifted in a vertical direction as seen in FIG. 3 from the input part 20 to provide a display.

During the shift action in the input part 20, the buses A , B and C are supplied sequentially with combined pulse voltages V_{A1} , V_{B1} and V_{C1} of the voltages V_1 and V_2 and the buses AL , BL and CL are grounded through a transistor $Q3$. In the shifting of the information to the display part 22, the buses AL , BL and CL are supplied sequentially with combined pulse voltages V_{AR} , V_{BR} and V_{CR} of the voltages V_1 and V_2 and the buses A , B , C and D are grounded through transistors $Q2$ and $QD2$. In the case of providing a stationary display in the input and display parts, the pulse voltages V_{AR} and V_{A1} or V_D and V_{AR} of the voltage V_1 are impressed only between the buses AL and A or between buses D and AL .

The voltages V_1 , V_2 and V_3 bear such a relation that $V_1 < V_2 < V_3$. In the shift action in the input part 20, the voltages, for example, V_{B1} and V_{C1} , are selected at V_2 to facilitate shifting from the electrode connected with the bus B to that connected with the bus C . Then,

the voltages V_{B1} and V_{C1} are selected at V_1 and V_2 , respectively, and the impression of the voltage V_{B1} is stopped to erase the discharge on the electrode connected to the bus B . In this case, after transistors $QB2$ and $QC2$ are turned on to impress the voltage V_2 , transistors $Q2$ and $Q4$ are turned on to discharge the stored charges. Then, transistors $QB1$ and $QC2$ are turned on and transistors $Q2$ and $Q4$ are turned off. Thereafter, by repeating the same procedures, the discharge spot can be shifted from the electrode connected with the bus C to that connected with the bus A . Further, by repeatedly impressing the pulse of the voltage V_1 to a desired bus, written information can be displayed stationary by the wall charge.

FIGS. 4A to 4E are a series of waveform diagrams for explaining writing and shifting in the input part 20. After transistors $QR1$ ..., QRi are turned on selectively by the written information to be supplied with a voltage $-(V_3-V_1)$, a transistor $QRS1$ is turned on and then a transistor QR is turned on to be supplied with the voltage V_1 and, further, a transistor $QRS2$ is turned on and, as a result of this, a voltage of a waveform V_{Ri} in FIG. 4A is impressed. Further, after a transistor $QW1$ is turned on to be supplied with the voltage V_1 , transistors $Q2$ and $Q4$ are turned on and a transistor $QW2$ is turned on to be supplied with the voltage V_2 , after which the transistors $Q2$ and $Q4$ are turned off and, further, the transistor $QW2$ is turned on and then the transistors $Q2$ and $Q4$ are turned on, thus impressing a voltage having a waveform V_w in FIG. 4B to the bus W . In this manner, the write electrodes opposing the electrodes connected to the bus W are selected to produce a discharge. At the instant when the pulse of the voltage V_2 has been impressed to the bus W , a transistor $QB2$ is turned on to impress the pulse V_2 of the voltage V_{B1} to the bus B , performing the shift action. Thereafter, voltages of waveforms V_{B1} , V_{C1} and V_{A1} in FIGS. 4C to 4E are impressed by controlling the transistors $QA1$, $QA2$, $QB1$, $QB2$, $QC1$, $QC2$, $Q2$ and $Q4$ as described above, by which the shift operation is achieved in a sequential order.

The vertical shift to the display part 22 is the same as described above and the voltages V_{AR} , V_{BR} and V_{CR} similar to the aforementioned are impressed to the buses AL , BL and CL by controlling transistors $QAR1$, $QAR2$, $QBR1$, $QBR2$, $QCR1$, $QCR2$, $QD1$, $Q1$ and $Q3$ to achieve thereby the shift operation.

In the case of a stationary display in the display part 22, the display is continuously provided with the voltage V_1 as a sustain voltage by the control of the transistors QD , $QD2$, $QAR1$ and $Q3$.

As has been described in the foregoing, in the present invention, at the time of shift operation, the voltage V_2 lower than a usual firing voltage but higher than the sustain voltage in the case of the stationary display is impressed to adjacent electrodes to facilitate shifting of the discharge spot, and in this case, the minimum sustain voltage of the adjacent electrodes is raised by the formation of the discharge spot by the impression of the voltage V_2 , but the voltage V_1 , which is higher than the usual sustain voltage but lower than the raised minimum sustain voltage, is impressed to the preceding electrodes to erase the wall charge, so that the shifting speed can be enhanced. Since the voltages V_2 and V_1 are different only in magnitude and can be made identical in pulse width with each other, the control is simple and easy as compared with the system of impressing an

erasing pulse. Further, the circuit such as shown in FIG. 3 has the construction of a low impedance circuit, so that voltage fluctuation due to a discharge current is little and hence the operation is stable.

Numerous changes may be made in the above-described apparatus and the different embodiments of the invention may be made without departing from the spirit thereof; therefore, it is intended that all matter contained in the foregoing description and in the accompanying drawings shall be interpreted as illustrative and not in a limiting sense.

What is claimed is:

1. An energizing system for a gas discharge display panel including a first base plate and a first set of electrodes disposed thereon, and a second base plate and second set of electrodes disposed thereon to traverse said first set of electrodes for defining a discharge region at each of the intersections of said electrodes of said first and second sets, and said first and second base plates confining a discharge gas therebetween, said display panel having the characteristics that a firing voltage of a first magnitude applied between said electrodes of said first and second sets causes a discharge spot in the discharge region and a sustain voltage of a second magnitude less than the first magnitude applied between said electrodes of said first and second sets sustains said discharge spot in the discharge region, said energizing system comprising:

means for supplying a shift voltage pulse of a third magnitude less than the first magnitude and greater than the second magnitude,

means for applying said shift pulse, in a given time interval, between the electrodes of said first and second sets defining a discharge region at which a discharge spot exists and which is to be shifted to an adjacent discharge region and simultaneously applying a shift pulse between the electrodes of said first and second sets defining said adjacent discharge region and, in a successive time interval, applying a shift pulse only to said electrodes defining said adjacent discharge region and thereby to shift the discharge spot to the said adjacent discharge region.

2. The energizing system as claimed in claim 1 wherein there is further provided means for applying a voltage pulse of a lower magnitude than that of the shift pulse during said successive time interval between the electrodes of said first and second sets intersecting at said given discharge region from which said discharge spot was shifted, thereby to positively extinguish the discharge spot at said given discharge region.

3. The energizing system as claimed in claim 2, wherein said lower magnitude pulse is of the second magnitude.

4. The energizing system as claimed in claim 3, wherein there is further provided a plurality of first buss electrodes and said first set of electrodes is divided into a plurality of groups of electrodes, the corresponding electrodes of each of said groups being connected to respectively associated ones of said plurality of first buss electrodes.

5. The energizing system as claimed in claim 4 wherein said sustain voltage applying means includes a first plurality of switch means, each connected to said sustain voltage supplying means for applying selectively the sustain voltage to a corresponding one of said first buss electrodes, and said shift pulse applying means in-

cludes a second plurality of switch means, each connected to said shift voltage pulse supplying means for applying selectively the shift voltage pulse to a corresponding one of said first buss electrodes.

6. The energizing system as claimed in claim 4, wherein there is further provided a plurality of second buss electrodes, and said second set of electrodes is divided into a plurality of groups of electrodes, corresponding electrodes of each of said groups of electrodes of said second set being connected to respectively corresponding ones of said plurality of second buss electrodes.

7. The energizing system as claimed in claim 6, wherein there is included a third plurality of switch means, each connected to a corresponding one of said second buss electrodes for applying the sustain voltage thereto, and a fourth plurality of switch means, each connected to a corresponding one of said second buss electrodes for selectively applying the shift voltage pulse thereto.

8. An energizing system for a gas discharge display panel including a first base plate and a first set of electrodes disposed thereon, and a second base plate and a second set of electrodes disposed thereon to traverse said first set of electrodes for defining a discharge region at each of the intersections of said electrodes of said first and second sets and said first and second base plates confining a discharge gas therebetween, said display panel having the characteristics that a firing voltage of a first magnitude applied between said electrodes of said first and second sets causes a discharge spot in the discharge region and a sustain voltage of a second magnitude less than the first magnitude applied between said electrodes of said first and second sets sustains said discharge spot in the discharge region, said energizing system comprising:

means for supplying said sustain voltage of the second magnitude;

means for applying said sustain voltage during predetermined time intervals, between the electrodes of said first and second sets defining a discharge region at which a discharge spot exists and which said discharge spot is to be shifted to a discharge region thereto;

means for supplying a shift voltage pulse of a third magnitude less than the first magnitude and greater than the second magnitude; and

means for applying said shift voltage pulse to the electrodes of said first and second sets defining said adjacent discharge region during at least the last of said predetermined time intervals in which the sustain voltage is applied to said discharge region at which said discharge spot exists, thereby to shift the discharge spot to said adjacent discharge region.

9. The energizing system as claimed in claim 8, wherein each of said first and second sets of electrodes includes first and second pluralities of said electrodes, and wherein:

said first plurality of electrodes of said first set traverses said first plurality of electrodes of said second set, defining discharge regions at the intersections thereof, and comprising an input portion of said display panel, and

said second plurality of electrodes of said first set traverses said second plurality of electrodes of said second set defining discharge regions at the inter-

sections thereof comprising a display portion of said display panel.

10. The energizing system as claimed in claim 9, wherein there is further provided a common write electrode disposed upon said first base plate and a plurality of write selection electrodes disposed upon said second base plate and traversing said common write electrode, each of said write selection electrodes being associated

with a corresponding group of said first plurality of electrodes of said second set.

11. The energizing system as claimed in claim 10, wherein there is included a write means for applying a write signal of said first magnitude between the common write electrode and at least a selected one of the write selection electrodes.
